Halcyon Adventure Inflatable Paddleboard with Backpack and Pump 2023, site visited Nov. 2, 2023, Aqua-Leisure: <https://aqualeisure.com/product/halcyon-adventure-inflatable-paddleboard-with-backpack-and-pump/> (Year: 2023).*

Primary Examiner — Michael C Stout*Assistant Examiner* — Melvin L Davis(74) *Attorney, Agent, or Firm* — Wolf, Greenfield & Sacks, P.C.(57) **CLAIM**

The ornamental design for the paddleboard, as shown.

DESCRIPTION

FIG. 1 is a perspective view of the paddleboard in accordance with our new design.

FIG. 2 is a top plan view of the paddleboard.

FIG. 3 is a bottom plan view of the paddleboard.

FIG. 4 is a left-side elevational view of the paddleboard of FIG. 2.

FIG. 5 is a right-side elevational view of the paddleboard.

FIG. 6 is a front elevational view of the paddleboard; and, FIG. 7 is a rear elevational view of the paddleboard.

The broken line showing of the paddleboard is for the purpose of illustrating portions of the article that form no part of the claimed design.
